UNITED STATES PATENT OFFICE.

GEORGE A. FREEBURG, OF ELGIN, ILLINOIS.

INDUCTANCE.

Application filed October 1, 1925. Serial No. 59,795.

This invention has to do with certain improvements in inductance coils and the like. It has to do especially with improvements in inductance coils for radio and other similar high frequency work. Nevertheless, it will be understood that the features of the invention may also be used in connection with coils for other classes of work than that above referred to.

10 The main object of the invention is to provide a coil of the general form of a toroid, so as to thereby largely eliminate outside or cross interference between the coil and other outside devices. Toroid coils are well known and understood in the radio field, but the coil herein disclosed presents certain new features of construction and the method of construction is also novel.

One of the objects of the invention is to 20 provide a coil of the general form of a toroid and in which the various turns are so criss-crossed and related with respect to each other as to largely eliminate interturn capacity. More particularly in this connection, it is an object to provide what may be designated a basket weave in a toroid form of coil.

Another feature of the invention relates 30 to the provision of a coil construction which is so arranged as to reduce the amount of dielectric in contact with the turns of the coil to a very low amount so as to correspondingly reduce the self-capacity of the coil. In this connection, it is an object to, 35 at the same time, establish a coil having sufficient mechanical rigidity and strength to stand up in commercial work and shipment.

More particularly it is an object to establish the support for the coil turns by 40 means of the same devices which serve to retain the various turns in their basket weave form.

A further object of the invention is to 45 make provision for the incorporation of the features of the present invention in toroid coils either in the form of ordinary plain inductances or in the form of transformers. In the latter case, provision is 50 made for the insertion and support of a primary coil centrally placed within the body of the secondary coil, both coils being of toroid form.

Another feature of the invention relates 55 to the provision of an improved method of

winding the coil, and also the provision of a simple coil winding machine for doing this work.

Other objects and uses of the invention will appear from a detailed description of the same, which consists in the features of construction and combinations of parts hereinafter described and claimed.

In the drawings:

Figure 1 shows a side elevation of a completed coil embodying the features of the present invention, the same being carried by a simple form of support;

Fig. 2 shows a vertical cross section on the line 2—2 of Fig. 1, looking in the direction of the arrows;

Fig. 3 shows a side elevation of a coil wound in basket form according to one feature of the present invention, the coil being illustrated in substantially the condition in which it is removed from the winding machine;

Fig. 4 shows a view similar to that of Fig. 3, with the exception that a primary coil has been set into place as would be the case in the manufacture of a transformer proper;

Fig. 5 shows a view of the coils of Fig. 4 after they have been bent around into toroid form and strips of cane have been woven into place;

Fig. 6 shows a side view of a simple construction of winding machine for winding the coils of the present invention;

Fig. 7 shows a cross section on the line 7—7 of Fig. 6, looking in the direction of the arrows; and

Fig. 8 shows a cross section on the line 8—8 of Fig. 6, looking in the direction of the arrows.

Referring first to Figs. 1 and 2, the toroid coil is designated in its entirety by the numeral 9. It includes the successive convolutions 10 which are of generally circular form, and which convolutions lie substantially within different planes radiating out from a common axial center. The turns of the coil are continuously connected together, so that the coil is electrically continuous around the entire circle.

The different convolutions are individually of substantially the same diameter, and they are all supported substantially a fixed distance from the common axial center. Consequently, the turns establish a "toroid" as clearly evident from Figs. 1 and 2.

The coil as a unit is conveniently supported in any suitable manner, as by the use of a pair of center hub blocks 11 and 12, which are circular and of slightly larger size than the axial diameter of the toroid. These hub blocks are drawn together by a center bolt 13, as shown in Figs. 1 and 2.

Preferably a bracket plate 14 is secured to the hub support thus established, said bracket plate reaching down at one side of the toroid and then across beneath the same so as to establish a foot or pedestal 15 for the support of the coil. This bracket plate 14 may at its upper end draw in and lay flat against the hub block 12 and be secured thereto by the through bolt 13, already referred to.

The pedestal 15 is bent upwards and then backwards on an angle, as shown at 17, so as to establish in effect a panel board to accommodate the terminal connectors 18, 19, 20 and 21 for the ends of the coils. Two of these connectors 20 and 21 are for the two ends of the toroid coil, already referred to, and the other two connectors are for the ends of a primary coil, should such coil be used. In the case of a plain inductance not being a primary, the connectors 18 and 19 will be dispensed with, and the panel board 17, in such case, may be shortened up and the terminal connectors 20 and 21 placed centrally thereon.

Examination of Fig. 2 in particular will show that the inner portions of the convolutions of the toroid 10 are crisscross in a "basket weave". This is done by passing each turn alternately to the inside and then to the outside of the adjoining turns according to the selected form of weave. It is well understood that this type of weave tends to reduce the interturn capacity of the coil, and, as far as I am aware, my present invention is the first instance of the application of this principle to the general form of toroid coils.

The various turns of the toroid are retained in the basket form of weave in any convenient manner, but, for this purpose, I have illustrated the encircling strips of reed, 22, 23, 24, 25 and 26, which reach around through the central portions of the convolutions of the toroid in such a manner as to establish the desired criss-crossing of the successive convolutions, and also to establish a satisfactory mechanical support for the turns of the toroid.

In the particular weave illustrated, there are five of these encircling rings 22, 23, 24, 25 and 26, and it will be noted that each convolution passes first to the outside of two of the rings and then to the inside of the third. These rings are preferably of fibrous material, such as strips of reed or other similar material such as pyrolene, celluloid, etc., having a relatively low dielectric capacity. Furthermore, material of this kind is relatively

flexible and strong and does not break except when bent on very sharp angles, and is, therefore, very well adapted for weaving into the convolutions of the coil during the process of manufacture as well as being well adapted to establish the necessary permanent support when completed.

It will be noted from examination of Fig. 1 that the reed may be used in the form of a continuous strip woven around through the necessary number of complete turns and through the different convolutions of the coil. It will be found, in practice, that a continuous strip of reed material may be wound through the different convolutions and stepped from turn to turn without difficulty, as illustrated in Fig. 1.

In order to give additional rigidity to the coil, I prefer to bind the convolutions together by the use of strings or threads 27 and 28 which are carried around through the body of the toroid and tend to draw the convolutions thereof against the center ring 24. In many cases the use of these strings will be found unnecessary.

When it is desired to provide a primary coil, the same may be established in the form of an inside toroid 29, generally of considerably fewer turns than the outside or main toroid 9.

Referring to Figs. 3, 4 and 5, I will explain one method of winding the coils and bringing them into the general form of the construction illustrated in Figs. 1 and 2. The toroid coil 9 is first wound as a substantially straight cylinder, rods, such as 30, being woven through the various convolutions in the proper manner to establish the desired basket weave. It is seen that the convolutions are placed close together in both Figs. 3 and 4. In Fig. 4 there is also illustrated the primary coil 29 which is set loosely through the main toroid 9. In these cases in which the present invention is used only in connection with a plain inductance this primary coil will not be used.

By removing one of the rods from the coil a strip of reed may be run through the spaces so vacated, and then the next rod may be removed and the end of the reed strip run through the coil spaces so vacated. In like manner, the various remaining rods may be successively removed and the reed strip run successively through the vacated spaces. Thereafter the reed strip may be gradually tightened up until finally the entire coil is brought into the desired toroid form.

During the above operation, the end portions of the toroid will be kept slightly separated from each other, as indicated in Fig. 5, and upon completion of the process of weaving the reed strip into place, the convolutions may be evened out so as to bring the entire toroid into a balanced condition around the entire circle.

In those cases in which a primary coil is used, it may be allowed to rest loosely within the body of the toroid during the above operation, and after the weaving process has 5 been completed, the primary may be stretched out into the complete circle and secured in position to establish a primary toroid coil.

After completing the coil 9 it will generally be desirable to tie a pair of strings 10 around through its interior portion, as indicated at 27 and 28 in Fig. 2. When a primary is used it will rest upon these strings 27 and 28, and if desired, another 15 string 31 may be passed around through the interior of the primary and then tied so as to hold the convolutions of the primary uniformly and firmly distributed around the circle.

20 Referring to Figs. 6, 7 and 8, I will now explain the machine therein illustrated for automatically winding the coil 9 up to the condition illustrated in Fig. 3.

This machine includes a longitudinally 25 extending shaft 32 carried in bearings in suitable brackets 33, 34 and 35. Any convenient means may be provided for driving the shaft.

Upon this shaft is mounted a gear 36 30 which drives a pinion 37 on a stub shaft 38 in a ratio of 3 1/3 to 1. That is, the shaft 38 makes 3 1/3 revolutions for each revolution of the shaft 32. At its outer end the stub shaft 38 carries a crank pin 39 which 35 swings a bell crank 40 pivoted at the point 41, a suitable connection being established between the pin 39 and the bell crank 40 by means of a link 42. The other arm 43 of the bell crank is forked and is connected to a 40 sleeve 44 by a pin and slot connection 45.

Journalized upon the shaft 32 is a spool 45 including the barrel 46 and the end heads 47 and 48. A collar 49 is secured to the shaft 32 and has a pin 50 reaching out from its back face in position to receive a corresponding socket in the spool head 48. In this way, the spool is rotated in harmony with the shaft 32.

Extending axially through the two spool 50 heads 47 and 48 are ten rods or pins designated 51, 52, 53, 54, 55, 56, 57, 58, 59 and 60. Five of these are provided with outwardly extending fingers, such as 61 in Fig. 7, the other five being plain, as shown in said figure.

The hub 44 carries a flange 62 to which is secured an inwardly reaching finger 63 in position to engage one or the other of the fingers 61 depending upon the position of 60 the spool. In this connection, it will be noted that as the spool rotates, the pins 51-60 travel therewith, so that the fingers 62 are carried successively past the position of the finger 63.

65 When the bell crank is swung the finger

63 is drawn to the left and will simultaneously draw back the particular pin which stands in the proper position for engagement of its finger 61 by the finger 63. This will result in the withdrawal of said pin 70 momentarily from the right hand end of the spool. Normally the winding of the wire proceeds on the different pins, but in case of the momentary retraction of a pin, it is evident that the convolution will at that 75 point fall below the normal level and cause the establishment of a basket weave.

When the bell crank is again restored to the position indicated in Fig. 6, the flange 62 will force back and restore the pin which 80 was so retracted, so that thereafter the winding will proceed on the outside of said pin until it is again retracted.

In order to keep the convolutions in satisfactory order during the winding process, I 85 prefer to place a sliding plate 64 on the spool and pins, the same being slidably mounted with sufficient friction to keep the convolutions closely packed, but nevertheless it allows said plate to slide over as the 90 operation progresses. I also prefer to place another sliding plate 65 on the spool adjacent to the position of the hub 47. This plate is provided with a series of buttons 95 66 which are spring pressed outwards by the spring 67, and their outer ends may be engaged by the flange 68 of a swinging arm 69 pivoted at the point 70. A rod 71 is slidably mounted in the base 72 and is normally retracted by a spring 73 so as to 100 bring its shoe 74 against a finger 75 on the flange 62.

A thumb screw 76 on the lever 69 bears against the outer end of the sliding bar 71 and permits the parts to be properly adjusted. As a result the restoring movement of 105 the sleeve 44 under the impulse of the bell crank serves to force the bar 71 to the right, and thus swing the arm 69 and force the spool head 65 under spring pressure against 110 the newly wound convolution.

Owing to the fact that the gear ratio between the gears 36 and 37 is 3 1/3 to 1, it follows that the bell crank 40 will be swung a complete back and forth movement during 115 3/10 of a revolution of the shaft 32 and the spool, so that the spool will advance the distance of three rods between complete bell crank swings. As a result, the finger 63 will also skip at least two of the rods, thus causing the convolutions to stay outside of two rods and drop beneath the third rod during the winding operation.

From the above it will be seen that I have provided means for automatically winding 125 the basket weave coil in the desired manner. It will also be noted that the basket weave condition is only presented around the inner half of the toroid. If desired, the basket weave could be continued around the entire 130

surface of the toroid, including its outer half, but ordinarily this will be unnecessary, and in some respects, may be undesirable.

While I have herein shown and described only certain embodiments of the features of my present invention, still I do not intend to limit myself to the same, except as I may do so in the claims.

I claim:

1. As a new article of manufacture, an inductance unit for the purpose specified comprising a continuous coil in the shape of a toroid having its convolutions lying substantially in planes extending substantially radial with respect to its axis, the inner portions of the successive convolutions criss-crossing each other within the inner half of the toroid to establish a basket weave around said inner half of the toroid, a continuous length of flexible fibre reed extending around the inner half of the toroid and between criss-crosses of successive convolutions thereof within said basket weave portion, a pair of binding cords extending around the inner portion of the toroid to draw the convolutions thereof firmly together, another toroid coil centrally located within the toroid aforesaid, and a cord extending around through the second mentioned toroid coil to draw the same firmly against the first mentioned cords, substantially as described.

2. As a new article of manufacture, an inductance unit for the purpose specified comprising a continuous coil in the shape of a toroid having its convolutions lying substantially in planes extending substantially radial with respect to its axis, the inner portions of the successive convolutions criss-crossing each other within the inner half of the toroid to establish a basket weave around said inner half of the toroid, a continuous length of flexible fibre reed extending around the inner half of the toroid and between the criss-crosses of successive convolutions there-

of within said basket weave portion, and a pair of binding cords extending around the inner portion of the toroid to draw the convolutions thereof firmly together, substantially as described.

3. As a new article of manufacture, an inductance unit for the purpose specified comprising a continuous coil in the shape of a toroid having its convolutions lying substantially in planes extending substantially radial with respect to its axis, the inner portions of the successive convolutions criss-crossing each other within the inner half of the toroid to establish a basket weave around said inner half of the toroid, and a continuous length of flexible fibre reed extending around the inner half of the toroid and between the criss-crosses of successive convolutions within said basket weave portion, substantially as described.

4. As a new article of manufacture, an inductance unit for the purpose specified comprising a continuous coil in the shape of a toroid having its convolutions lying substantially in planes extending substantially radial with respect to its axis, the inner portions of the successive convolutions criss-crossing each other within the inner half of the toroid to establish a basket weave around said inner half of the toroid, and means for securing the convolutions in proper position with respect to each other, substantially as described.

5. As a new article of manufacture, an inductance unit for the purpose specified comprising a continuous coil in the shape of a toroid having its convolutions lying substantially in planes extending substantially radial with respect to its axis, those portions of the successive convolutions lying in one half of the toroid criss-crossing each other within said half of the toroid to establish a basket weave around said half of the toroid, substantially as described.

GEORGE A. FREEBURG.
